UNITED STATES PATENT OFFICE.

WARNER E. McMULLAN AND HENRY JAMES HICKEY, OF FORT DODGE, IOWA.

DESIGN FOR A HIGHWAY-GUIDE DEVICE.

56,102.

Specification for Design.

Patented Aug. 17, 1920.

Application filed March 20, 1920. Serial No. 367,491. Term of patent 14 years.

To all whom it may concern:

Be it known that we, WARNER E. McMULLAN and HENRY J. HICKEY, citizens of the United States of America, residing at Fort Dodge, in the county of Webster and State of Iowa, have invented a new, original, and ornamental Design for a Highway-Guide Device, of which the following is a specification, reference being had to the accompanying drawing, forming a part thereof.

Figure 1 is a face view and Fig. 2 an edge view of a guide device showing our new design.

We claim:

The ornamental design for a highway guide device, as shown.

WARNER E. McMULLAN.
HENRY JAMES HICKEY.
